EXHAUST TUBULATION

Walter H. Van Dyke, Peabody, Mass., assignor to
 Sylvania Electric Products Inc., Salem, Mass.,
 a corporation of Massachusetts

Application March 29, 1947, Serial No. 738,158

1 Claim. (Cl. 313—317)

1

This invention relates to electric discharge devices and more particularly to those containing a quantity of mercury therein.

An object of this invention is to provide a means for preventing the mercury from being drawn off from the device during the evacuation process.

Another object is to accomplish the first mentioned object in such a manner that not only will the evacuation process not be deleteriously affected but will actually be aided and its efficiency increased thereby.

Further objects, advantages and features will be apparent from the following specification taken in conjunction with the accompanying drawing in which:

The figure is a side elevational view of a lamp, in which it is desired to seal a quantity of mercury, connected to a vacuum pump, a supply of an inert gas such as argon, and a mercury dispenser.

In the manufacture of electric gaseous discharge devices and more particularly fluorescent lamps, it has been found desirable to introduce a quantity of mercury into the lamp at some point during the manufacturing process. This may well be done when the elongated glass envelope, with a pair of filamentary electrodes sealed at each end thereof, is heated and evacuated, the evacuation taking place through an exhaust tubulation projecting from an end of the elongated glass envelope. The mercury may be introduced in any one of several ways. For example, it may be introduced in the form of a mercury bomb of the type shown in U. S. Patent 2,283,189 issued May 19, 1942. It may also be introduced from an external source, such as a dispenser of the type shown in U. S. Patent 2,203,612 issued June 4, 1940, for example.

In the accompanying figure, the lamp comprises an elongated tubular glass envelope 1 which has a coating of luminescent material 2 on the inner wall thereof and the mounts 3 and 4 sealed in the ends thereof. The lead-in wires 5 sealed in the mounts 3 and 4 and projecting upwardly therefrom support the filamentary electrodes 6. The exhaust tubulation 7 extends from one end of the elongated tubular glass envelope and is projected up into the lower end of a rubber washer 8 on which sufficient pressure is exerted to hold the envelope 1 suspended by its exhaust tube.

One end of a manifold 9 is connected to the upper end of the rubber washer 8. To this manifold 9 there is connected a vacuum pump 10, a

5 supply 11 of an inert gas such as argon, and a mercury dispenser 12. Control over the establishment of connections between the manifold 9 and the vacuum pump 10, the inert gas supply 11, and the mercury dispenser 12 may be exercised through valves 13, 14, and 15 respectively.

10 In the evacuation of the tubular glass envelope according to my invention, the envelope is located in an oven in which it is heated, a quantity of mercury is vaporized in said envelope, it is subjected to a series of evacuating and flushing steps, the filamentary electrodes are subjected to a series of heating steps, and a final filling of an inert gas at the desired pressure is introduced 15 therein before it is finally sealed and severed from the exhaust tubulation. This oven 21 comprises a pair of walls 16, a roof 17, and a floor 18. The roof 17 is provided with a small aperture therein, through which the exhaust tubulation 7 may extend. Heating elements 19 are suspended within the area defined by the walls 16 and may be energized by connecting them to a source of 20 electrical energy through the insulating sleeves 20 which project through the walls 16.

25 During the series of evacuating and flushing steps which comprise the exhaust cycle, a quantity of an inert gas such as argon is introduced into the envelope to mix with the volatilized foreign gases which it is desired to remove from the envelope before it is finally sealed. This series of alternate evacuating and flushing steps has been found to enable the attainment of a relatively high vacuum. However, I have found that an even higher degree of vacuum may be attained 30 during the evacuation process by introducing into the envelope 1 a quantity of mercury 22. The heat of the oven is sufficient to vaporize the mercury which then diffuses with the volatile gases and acts like a diffusion pump.

35 As this mercury vapor aids in sweeping the volatile gases the entire length of the elongated envelope, it actually passes out of the envelope and into the exhaust tubulation. There is a sharp difference in the temperature of that portion of the exhaust tube which has been firmly held within the rubber washer 8 throughout the exhausting process as compared to the temperature of that portion of the exhaust tube below the rubber. The lower portion of the exhaust tube has been exposed to all the heat to which the elongated envelope itself was exposed in the heating oven, whereas the portion within the rubber 40 8 has been protected so that it remains relatively quite cool. The vaporized mercury will,

therefore, condense on the cool portion of the wall of the exhaust tube.

Since the mercury is introduced into the envelope not only to aid in the evacuation thereof but also to be permanently sealed therein, it is necessary to either drive the condensed mercury 23 back into the envelope or introduce an additional quantity thereof so that a predetermined amount will be finally sealed therein. Normally, the force exerted by the inert gas, usually argon, which is used to flush the envelope and to provide a final filling thereof which is sealed therein, is not sufficient to overcome the surface tension between the condensed mercury and the wall of the exhaust tubulation. Therefore some means must be employed to effect the dislodging of the condensed mercury.

In my Patent 2,313,788 I pointed out that etching of the exhaust tubulation will roughen the inner wall thereof enough to reduce the surface tension to a point where the force exerted by the inrushing gas will be great enough to drive the mercury back into the envelope. However, I have found that etching weakens the exhaust tubulation and causes higher spoilage of lamps at this stage of the manufacturing process.

I have, therefore, developed a means of effecting the dislodging of the condensed mercury without weakening the exhaust tubulation. I accomplish this by coating the clear glass, normally used in lamp manufacturing practice for exhaust tubulations, with an anti-wetting substance, such as monethyl chlorosilane, which remains stable chemically when subjected to the heat of a lamp exhaust machine. This coating of an anti-wetting substance causes the mercury to condense in the form of droplets rather than in the form of a mist or fog as is the case when the exhaust

tubulation is uncoated or unetched. The reduction of the surface tension which is thereby effected is sufficient to enable the inrushing inert gas to drive the condensed mercury back into the lamp and perform the same "diffusion pump action" described above.

Since, as was mentioned above, the lamp receives a final filling of an inert gas before it is finally sealed, this final introduction of gas will dislodge the condensed mercury on the wall of the exhaust tubulation and force it back into the lamp before the exhaust tubulation is severed therefrom.

Although I have mentioned above the use of monoethylchlorosilane as an exhaust tubulation coating material which has proven advantageous, any anti-wetting substance, which will withstand the lamp exhaust temperatures, may be used without departing from the spirit of my invention.

What I claim is:

An electric gaseous discharge lamp comprising a glass envelope, electrodes mounted within said envelope, a filling of inert gas within said envelope, a quantity of mercury within said envelope, an exhaust tubulation extending from said envelope, and a coating of monoethylchlorosilane on the inner wall of said tubulation.
